UNITED STATES PATENT OFFICE.

GEORG WESENBERG, OF ELBERFELD, GERMANY, ASSIGNOR TO FARBENFABRIKEN VORM. FRIEDR. BAYER AND CO., OF LEVERKUSEN, NEAR COLOGNE-ON-THE-RHINE, GERMANY.

MEDICAL COMPOUND.

No Drawing.

Application filed February 15, 1924. Serial No. 693,124.

To all whom it may concern:

Be it known that I, GEORG WESENBERG, a citizen of Germany, residing at Elberfeld, State of Prussia, Germany, have invented

5 new and useful Improvements in Medical Compounds, of which the following is a specification.

The present invention relates to new and useful improvements in a medical compound 10 being a valuable anodyne for nervous headache, catarrhs of the nose and throat, pains of the stomach, nausea, vomiting (seasickness) etc.

The new composition comprises an alkyl oxyacetyl compound of menthol (see U. S. Letters Patent No. 836,914) and a halogenated naphthol in varying proportions with the addition of suitable compounds. A valuable preparation has e. g. the following 20 composition:

0.5 grams sugar.

0.0015 grams tribromo-beta-naphthol.

0.0015 grams ethoxyacetylmenthol.

0.0015 grams raspberry essence.

0.005 grams gelatine.

25

0.0015 grams stearin.

From this mixture a tablet is fabricated.

For use it is taken by the mouth where by the action of the spittle the effective substances display their antiseptic properties. 30

I claim:—

1. A new medical composition of matter containing an alkyl oxyacetyl compound of menthol and a halogenated naphthol, substantially as described. 35

2. A new medical composition of matter containing ethoxyacetylmenthol and tribromo-beta-naphthol, substantially as described.

In testimony whereof I have hereunto set 40 my hand.

GEORG WESENBERG.
